DESIGN FOR A FINGER RING

George P. Wagner, Edgewood, R. I., assignor to
Uncas Manufacturing Company, a corporation
of Rhode Island

Application July 22, 1944, Serial No. 114,516

Term of patent 14 years

(Cl. D45—10)

To all whom it may concern:

Be it known that I, George P. Wagner, a citizen of the United States, residing in Edgewood, county of Providence, and State of Rhode Island, have invented a new, original, and ornamental Design for a Finger Ring, of which the following is a specification, reference being had to the accompanying drawing, forming a part thereof.

Fig. 1 is a top plan view;

Fig. 2 is a side elevational view of a finger ring showing my new design; and

Fig. 3 is a sectional view taken substantially on line 3—3 of Fig. 1.

The leaf arrangement as shown in Fig. 2 is repeated on the opposite side of the finger ring.

I claim:

The ornamental design for a finger ring, substantially as shown and described.

GEORGE P. WAGNER.
